(57) **CLAIM**

The ornamental design for a bottle, as shown and described.

DESCRIPTION

FIG. 1 is a top, right, front perspective view of a bottle embodying my new design;

FIG. 2 is a front elevational view thereof, the rear elevational view being a mirror image of the front view shown except for the unclaimed threads;

FIG. 3 is a left side elevational view thereof;

FIG. 4 is a right side elevational view thereof;

FIG. 5 is a top plan view thereof; and,

FIG. 6 is a bottom plan view thereof.

The broken lines shown in the drawings are for illustrative purposes only and form no part of the claimed design.

In a preferred embodiment, the nature of this product is a bottle suitable for holding and dispensing cleaning solution.
